(57) **CLAIM**

The ornamental design for analyte-determining meter, as shown and described.

DESCRIPTION

FIG. 1 is a top perspective view of an analyte-determining meter.

FIG. 2 is a top plan view of the analyte-determining meter of FIG. 1.

FIG. 3 is a first side view of the analyte-determining meter of FIG. 1.

FIG. 4 is a bottom plan view of the analyte-determining meter of FIG. 1.

FIG. 5 is a second opposing side view of the analyte-determining meter of FIG. 1.

FIG. 6 is a first end view of the analyte-determining meter of FIG. 1; and,

FIG. 7 is a second opposing end view of the analyte-determining meter of FIG. 1.

The broken lines in the drawings are for illustrative purposes only and form no part of the claimed design.
